UNITED STATES PATENT OFFICE.

JOSEPH BLAUSTEIN, OF BROOKLYN, NEW YORK.

CUP.

Application filed May 22, 1925. Serial No. 32,044.

The objects of this invention are to secure an improved cup in which plates that normally lie flatwise together can be bowed apart with their side and bottom edges in engagement to form an interior space or chamber, as for drinking purposes, the cup normally being flat for convenience in packing or carrying in one's pocket; to provide means for operating said plates to expand or 10 open the cup and to return it to closed or flattened form; to secure such operating means as can be permanently connected to the plates to avoid separation and loss; to provide means for preventing escape of the 15 plates from each other when the cup is closed; to provide an operating lever which is out of the way when the cup is opened and when it is closed extends over the mouth of the cup to protect it, and to obtain other 20 advantages and results as may be brought out by the following description.

Referring to the accompanying drawings, in which like numerals of reference indicate the same parts throughout the several 25 views,

Figure 1 is a side view of the cup in closed or folded position;

Figure 2 is a similar view showing the cup open for use;

Figure 3 is a central vertical section on line 3—3, Fig. 1;

Figure 4 is a cross section on line 4—4, Fig. 1;

Figure 5 is a plan view of the top or 35 mouth of the open cup, as shown in Fig. 2, with the operating lever partly broken away, and

Figure 6 is a perspective view of said operating lever.

In the specific embodiment of the invention shown in said drawings, 1 and 2 indicate sheet metal plates forming the opposite sides of a cup, said plates normally lying flatwise together. The plate 1 has its 40 margins turned over as at 3 to receive the corresponding margin of the plate 2 and form a closure therewith, especially when the cup is distended or opened as by pressing inward upon the opposite edges of the top of the cup. This causes the plates 1 and 2 to bulge outwardly apart at the top of the cup, as shown in Figure 5, and in decreasing proportion all the way down to the bottom of the cup.

It will be noted that the plates 1 and 2 are of separate pieces, the plate 2 having an

edge adapted to fit in the groove at the edge of the plate 1 when the plates are bulged outwardly apart as described, and by my invention I provide means for bulging said plates which will force said edges into engagement to form a joint. Indeed, the said edges can be readily made so that a joint impervious to water or the like is formed when they are forced together by such means as hereinafter described.

The means which I have shown for operating said plates to open and close the cup consist of a rod or wire 4 extending across the top of the cup between the plates 1 and 2 and projecting through suitable holes in the marginal bend of the plate 1 to form the flange 3. At one end said rod 4 has a head 5 outside the cup and at its other end it has an eye 6 also outside the cup upon which is pivoted an operating lever 7 by means of which the cup is opened and closed. This operating lever has a head 8 with a cam surface 9 adapted to ride upon the edge of the cup and a handle portion 10 with an end clasp 11. Preferably this lever 7 is made of sheet metal doubled along the outer edge of the handle portion 10, so that its head 8 is composed of two opposite thicknesses of metal spaced by the wire or rod 4 between them, see Figure 6, and the end clasp 11 is formed by two diverging lugs which straddle the top of the cup in closed position of the same and hold it closed.

The operating lever 7 lies along the top of the cup, when the latter is closed, as shown in Figure 1, the inner end of the cam surface 9 permitting the top of the cup to expand edgewise and the handle 10 of the lever overlying the top of the cup to protect the same. I have shown the end clasp 11 at the middle of the top of the cup, but obviously it might be otherwise positioned, or the handle portion 10 of the lever might be extended beyond the end clasp to cover more of the top of the cup than shown.

To open the cup for use the lever is thrown outwardly into the position shown in Figure 2, its cam surface 9 riding upon the edge of the cup until a flattened rest 12 is reached at the outer end of the head 8 of the operating lever which positions said operating lever, as shown in Figure 2, to hold the cup open. After use, the lever is swung inwardly and the parts returned to the position shown in Figure 1.

Various modifications of construction may

be made in manufacturing my invention, without departing from the spirit and scope of the invention, and therefore I do not wish to be understood as limiting myself except as required by the following claims when construed in the light of the prior art.

Having thus described the invention, what I claim is:

1. The combination with a cup having a portion providing a groove extending between separated points of the top of the cup downwardly toward the bottom of the cup, and a separate plate with an edge adapted to fit said groove, of means for springing said grooved portion into engagement with said edge of the plate.

2. The combination with a cup having a portion providing a groove extending between separated points of the top of the cup downwardly toward the bottom of the cup, and a separate plate with an edge adapted to fit said groove, of means for springing said grooved portion into engagement with said edge of the plate and locking it there.

3. The combination with a cup having a side plate providing a marginal groove, and a separate side plate with an edge adapted to fit said groove, of means for bowing said grooved side plate into engagement with said edge of the other plate.

4. The combination with a cup having a side plate providing a marginal groove, and a separate side plate with an edge adapted to fit said groove, of means for exerting pressure upon opposite edges of said grooved side plate to force it into engagement with said edge of the other plate.

5. The combination in a cup having a portion providing a groove extending between separated points of the top of the cup downwardly toward the bottom of the cup, and a separate plate with an edge adapted to fit said groove, of means attached to said grooved portion for forcing it into engagement with said edge of the plate and for preventing escape of said plate when it is not so engaged.

6. The combination in a cup having a portion providing a groove extending between separated points of the top of the cup downwardly toward the bottom of the cup, and a separate plate with an edge adapted to fit said groove, of means attached to said grooved portion for forcing it into engagement with said edge of the plate and for

overlying the mouth of the cup when collapsed.

7. A cup comprising plates adapted to be bowed apart with their side and bottom edges in closed relation, a rod extending between said plates and outward at one edge thereof, and means on said rod for exerting pressure upon the edge of the cup.

8. A cup comprising plates adapted to be bowed apart with their side and bottom edges in closed relation, a rod extending between said plates and outward at one edge thereof, and means mounted on said rod for bowing said plates apart.

9. A cup comprising plates adapted to be bowed apart with their side and bottom edges in closed relation, a rod extending between said plates and outward at one edge thereof, and a cam on said rod for engaging the edge of the cup.

10. A cup comprising plates adapted to be bowed apart with their side and bottom edges in closed relation, a rod extending between said plates and outward at one edge thereof, and an operating lever on said rod having a rest to engage the edge of the cup and hold it open.

11. A cup comprising plates adapted to be bowed apart with their side and bottom edges in closed relation, and a bowing lever having a handle which when the cup is closed extends over the mouth thereof to protect it.

12. A cup comprising plates adapted to be bowed apart with their side and bottom edges in closed relation, and a bowing lever having a handle with means thereon for holding the said plates in closed position.

13. A cup comprising plates adapted to be bowed apart with their side and bottom edges in closed relation, and a bowing lever having a handle with an end clasp to straddle the said plates in closed position.

14. A cup comprising plates adapted to be bowed apart with their side and bottom edges in closed relation, and bowing means having a portion extending over the mouth of the closed cup to protect it.

15. A cup comprising plates adapted to be bowed apart with their side and bottom edges in closed relation, and a bowing lever of doubled sheet metal having a portion straddling the said plates in closed position.

JOSEPH BLAUSTEIN.
